Primary Examiner — Patricia A Palasik

(57) **CLAIM**

The ornamental design for a robot, as shown.

DESCRIPTION

FIG. 1 is a front view of a robot showing our new design;
FIG. 2 is a back view thereof;
FIG. 3 is a top view thereof;
FIG. 4 is a bottom view thereof;
FIG. 5 is a left side view thereof;
FIG. 6 is a right side view thereof; and,
FIG. 7 is a perspective view thereof.
